(57) **CLAIM**

The ornamental design for a display and dispensing cabinet, as shown and described.

DESCRIPTION

FIG. 1 is a front perspective view of a display and dispensing cabinet showing my new design.

FIG. 2 is a front elevational view thereof.

FIG. 3 is a right side elevational view thereof; the left side being a mirror image thereof.

FIG. 4 is a top plan view thereof; and,

FIG. 5 is a bottom plan view thereof.

The rear surface of the display and dispensing cabinet is not shown and forms no part of the claimed design.

The broken line showing of the container in a dispensing position in FIG. 1 is for illustrative purposes only and forms no part of the claimed design.
